ROBERT L. COONEY, OF ATLANTA, GEORGIA.

DRY-PIPE WATER-SERVICE FIRE-EXTINGUISHER SYSTEM.

1,075,021.

Specification of Letters Patent.

Patented Oct. 7, 1913

Application filed April 22, 1911. Serial No. 622,653.

To all whom it may concern

Be it known that I, ROBERT L. COONEY, a citizen of the United States, residing at Atlanta, in the county of Fulton and State 5 of Georgia, have invented new and useful Improvements in Dry-Pipe Water-Service Fire-Extinguisher Systems, of which the following is a specification.

This invention relates to improvements in 10 dry pipe water service fire extinguisher systems.

One of the objections to this class of fire protection service is the delay which intervenes between the moment of opening of the 15 distributing valve or sprinkler head at the time of a fire, and the moment at which the water is delivered upon the fire through the open distributing valve or sprinkler head. This delay may be divided into two periods, 20 the first and principal one of which is concerned with the opening of the dry pipe valve, and the second of which is concerned with the passage of water from the dry pipe valve to the open distributing valve or 25 sprinkler head.

The first period of delay referred to results from the facts that the dry pipe valve cannot open until the pressure of air in the distributing system has fallen below some 30 determined absolute degree, usually comparatively small; that the said pressure of air is normally maintained at a comparatively high degree in the distributing system; and that the only vent through which 35 the air may pass in order that the pressure may be reduced to the degree necessary to provide for the opening of the dry pipe valve is at that particular distributing valve or sprinkler head which happens to be open 40 at the time of a fire. This principal period of delay is greater or less in accordance with the extent of the system and the character of the dry pipe valve, but in all cases, even where the dry pipe valve may be of the most 45 efficient type in use, the delay is material and is sometimes fraught with serious consequences.

The second additional period of delay referred to and which is concerned with the 50 passage of the water from the dry pipe valve to the open distributing valve or sprinkler

head, is caused by a circumstance which in turn results from the nature of the ordinary dry pipe water service system, as set forth in the foregoing paragraph. This circumstance which materially increases the duration of the interval necessary for the passage of the water is found in the fact that the degree of pressure at which the dry pipe valve opens, is too low, or subsequent to the 55 opening of the dry pipe valve, becomes too low, to prevent the water, as it passes through the distributing system, from backing up in the closed leaders or laterals and trapping the air remaining therein until the 60 pressure of the trapped air equals the pressure of the water. The passage of the water from the dry pipe valve to the open distributing valve or sprinkler head is thus prevented from being direct and is caused to 65 have many useless and time consuming ramifications.

The object of the present invention is to reduce as far as possible the delay referred to in order that the water may reach the 70 scene of the fire at the earliest possible moment after the opening of a distributing valve or sprinkler head. In attaining this object the invention is concerned primarily and objectively with shortening the preliminary and principal period of delay, referred to, and incidentally with shortening the subsequent period of delay referred to. 75

Toward the attainment of the object stated the invention proposes a system which embodies the combination with the usual elements, viz., the water service pipe, the dry pipe valve, the distributing pipe and its leaders or laterals and the distributing valves or sprinkler heads, of an additional 80 element, viz., a means which operates to produce a venting of a portion of the air in the system immediately in advance of the dry pipe valve and concurrently with and independently of the venting of the air at the 85 open distributing valve or sprinkler head.

In the foregoing, as well as in the succeeding paragraphs, the word "air" as applied to the pressure medium normally contained in the distributing system is used 90 simply for the purpose of convenience, and is to be understood as including in its scope 95

any elastic fluid pressure medium which it may be desired to employ.

Embodiments of the invention are illustrated by way of example in the accompanying drawings, wherein—

Figure 1 is a diagram, partly in section, of a dry pipe water service fire extinguisher system in accordance with the present invention. This figure also shows what is thought to be a preferred construction of the additional element of the system. Fig. 2 is a sectional view, showing a slightly modified form of construction of the additional element, and Fig. 3 is a sectional view showing a further modified construction of the additional element.

Similar characters of reference designate corresponding parts throughout the several views.

20 The elements of the improved system, broadly considered, are the water service pipe A, the dry pipe valve B, the distributing pipe C with its leaders or laterals c and their sprinkler heads (or it might be distributing valves) c', and the element D by which the operation of the system is quickened in the manner generally referred to. The particular construction of the dry pipe valve B is immaterial, in so far as its relation to the present invention is concerned. This valve is, as usual, interposed between the water service pipe A and the distributing pipe C, its connection with these pipes as well as its valve head b immediately opposed to the column of water in the pipe A being shown only diagrammatically.

25 The distributing system (comprehending the pipe C and its leads or laterals c) is, as usual, charged with air at some determined degree of pressure. This static pressure holds the dry pipe valve in restraint by normally preventing, directly or through any desired intermediary, the unseating of the valve head b. When, however, any one 30 of the valves c' is opened, the pressure in the system is vented at this open valve and the operation of the dry pipe valve, i. e., the unseating of the head b is consequent, whereby water from the pipe A flows 35 through the pipe C and the open leader or lateral c, issuing at the open valve c'.

In the known systems the operation of the dry pipe valve may be characterized as directly consequent to i. e., dependent in the 40 first instance, upon the venting of air at the open sprinkler head or distributing valve. In the present system, while this venting of air at the open sprinkler head or distributing valve is the first and primary cause of operation, yet the unseating of the valve head b is not directly consequent to the venting of air at the open sprinkler head or distributing pipe in the sense in which this expression has been defined but is, in such 45 sense, directly consequent to the operation

of the element D and the operation of the element D is, in the same sense, directly consequent to the venting of air at the open sprinkler head or distributing valve. The operation of the element D is thus immediate with respect to the opening of a valve c' and mediate with respect to the operation of the dry pipe valve.

70 The element D constituting the means for quickening the operation of the system in the manner generally referred to is, with relation to the valve c', in the nature of an auxiliary vent valve and is operatively connected to the distributing pipe C directly in advance of the dry pipe valve B whereby a substantial fall of pressure in the distributing pipe consequent to the opening of a valve c' immediately results in the operation of the element D. The connections between the element D and the pipe C are, in the 75 preferred form of construction, furthermore of such nature that while they efficiently provide for the operation of the element D under the circumstances stated, they also provide against a premature operation of said element as a consequence of minute reductions of pressure in the distributing pipe incident to any slight leakage.

79 The element D in the embodiment shown in Fig. 1 consists essentially of a casing 1 having a vent opening 2, a valve head 3 normally closing the vent opening, and connections 4 and 5 between the casing and the distributing pipe C. The valve head 3 is provided at the upper end of a stem 6, slideable through a suitable guide 7 secured within the casing and carrying at its lower end a float 8 which has a low degree of buoyancy. The float 8 is normally supported by a body of liquid 9, e. g., water, which is 85 confined in a vessel 10 supported in the casing 1. The vessel 10 comprises two chambers 10^a and 10^b which communicate with one another and both of which are partially filled with the liquid 9. The chamber 10^a serves to confine the float 8 and the chamber 10^b forms in effect a downward and angular continuation of the connection 4, communicating directly with the latter and being separated from the chamber 10^a by a 90 pending partition 11.

95 The connection 4 communicates with the distributing pipe at a point in advance of the dry pipe valve and serves, in a manner to be explained, to transmit air from the 100 distributing pipe to the casing 1 from which it is vented through the opening 2. The connection 5 which communicates with the distributing pipe at a point in advance of the point of communication of the connection 4 and said pipe, is in the nature of a 105 by-pass and is provided with a diaphragm 12 having an aperture of "pin-hole" diameter.

110 In order to secure the best results it is 115

preferred to employ a check valve 13 having a pin-hole aperture and normally resting by gravity against a seat 14. The valve 13 is arranged in the distributing pipe C immediately in advance of the point of communication of the connection 5 and said pipe and serves to "block off" that portion C' of the distributing pipe which is immediately in advance of the dry pipe valve, 10 which includes the points of communication of the connections 4 and 5 and which extends to the valve 13.

The air with which the distributing system is charged fills the blocked off portion 15 C' of the distributing pipe, the connection 4, the casing 1, and the connection 5, air being passed from the portion of the pipe C in advance of the valve 13 to the portion C' of said pipe and the connection 4 through 20 the aperture in the valve 13, and being passed from the distributing pipe portion C' to the casing 1 through the aperture in the diaphragm 12. The pressure normally in the casing 1 and the distributing pipe 25 portion C' is thus equal to the pressure in the rest of the distributing system.

The operation, in detail, is as follows: At the time of a fire a valve c' is opened and thereupon air commences to vent at such 30 open valve. Immediately upon the venting of air at the sprinkler head a proportionate reduction of pressure occurs throughout the length of the distributing pipe, including the portion C' of said pipe. This fall of 35 pressure is permitted in the portion C' owing to the arrangement of the valve 13 which at this time is lifted from its seat by the expansive action of the pressure in the portion C'. This fall of pressure is not, however, 40 proportionately transmitted to the air in the casing 1, since the diaphragm 12 is fixed, the pin hole in said diaphragm is too small for this purpose, and the liquid 9 establishes a seal. Immediately, therefore,

45 upon a reduction of the pressure in the portion C', the pressure in the casing 1 becomes unbalanced and acts to shift the body of liquid 9, the said body of liquid under the influence of the pressure in the casing 1 being then forced through the connection 4 from whence it passes into that portion of the distributing pipe which intervenes between said connection 4 and the dry pipe valve. When the body of liquid is thus 50 shifted two new conditions are caused; first, the valve head 3 is moved to uncover the opening 2, since the float 8 descends consequent to the shifting of the body of liquid, and second, the seal normally maintained by 55 the body of liquid, is disestablished and the communication of the distributing pipe with the casing 1 is now uninterrupted through the pipe 4. Thereupon such pressure as remains in the blocked off portion C' immediately passes into the casing 1,

issuing from thence through the opening 2, which it may be noted has a larger diameter than the opening of the sprinkler head. Immediately that the pressure in the portion C' thus exhausts through the opening 2 the valve 13 is closed against its seat 14 by the greater pressure still remaining in the rest of the distributing system and thus the venting of this remaining pressure through the opening 2 is prevented to any appreciable extent. At the same time, the dry pipe valve opens and water flows into the portion C', raises the valve 13 and passes through the distributing system. The water as it passes through the portion C' also backs up in the connection 4, again filling the chambers 10^a and 10^b, reestablishing the seal and causing the valve head 3 to close against the opening 2. Since the valve 13 when it has been closed by the pressure remaining in the system, will not pass any appreciable degree of said pressure to the portion C', this remaining pressure necessarily has its only substantial exit at the open sprinkler head or distributing valve. On this account, as well as by reason of the fact that the closing of the valve 13 by the pressure remaining in the system and the opening of the dry pipe valve, take place practically at the same instant and immediately upon the venting of the pressure in the portion C', whereby only a momentary interval elapses before the water passes the valve 13, the pressure remaining in the system will still, during the passage of the water through the distributing pipe, have such degree as to prevent the water from backing up in the leaders or laterals and consequently the passage of the water to the open sprinkler head will be direct and without useless and time consuming ramifications.

While the valve 13 is not absolutely necessary to the efficient performance of the function of the element D its use is preferable since it provides for increasing the speed of 110 operation of the system by positively defining a certain restricted area (the portion C') directly in advance of the dry pipe valve which is immediately and absolutely vented and by positively separating this 115 area during the operation of the system from the rest of the distributing pipe. The valve 13, by virtue of the results stated in the preceding sentence, not only promotes a practically instantaneous relief of the dry 120 pipe valve but also positively provides for a sufficient degree of "remaining" pressure to prevent columning in the leaders or laterals.

The operations stated in the foregoing 125 take place almost instantly, the operation of the element D being nearly coincident with the opening of the sprinkler head and the operation of the dry pipe valve instantly succeeding the operation of the element D. 130

The pin-hole apertures in the diaphragm 12 and valve 13 provide, as stated, for the passage of air to the parts behind said diaphragm and valve when the system is charged, but do not allow of such passage to any appreciable or material extent during the operation of the system. These apertures are all of further utility in that they provide for the normal equalization of the pressure throughout the extent of the system and consequently prevent the element D from being affected by slight or minute and gradual reductions consequent to leakage. For this reason the element D cannot have any premature operation.

The construction of the element D shown in Fig. 2 differs from that shown in Fig. 1 only as to details of organization. In this case the vent hole 2 is formed in an end wall of the box and the valve head 3 is provided at the end of a lever 15 which at its other end is pivoted to the stem 6 of the float 8. The lever 15 adjacent the valve head, is provided with an arm 16 which is pivoted to the adjacent wall of the casing at a point below the opening 2. In other respects the construction is similar to that shown in Fig. 1.

In the construction shown in Fig. 3 the vent opening is arranged as in Fig. 2 and the valve head 3 is provided on a lever 17 pivoted by means of an arm 18 to the adjacent wall of the casing at a point below the opening 2. In this case the chamber 10 previously referred to is not employed as a separate element, its main function being served by the lower portion of the casing in which the body of liquid 9 is confined. The said lower portion of the casing is divided by a partition wall 19 into liquid containing chambers 1^a and 1^b which have a relation similar to the chambers 10^a and 10^b previously described. The connection 4 communicates directly with the casing at a point above the partition wall 19 and in this instance serves additionally the function of the connection 5 shown in the preceding examples. For this purpose an inwardly swinging check valve 20 having a pin-hole aperture is provided above the partition wall 19, the lower edge of this check valve resting upon the wall. The lever 17 carries at its free end a ball member 21 which, when out of the body of liquid 9, has the function of a weight and when immersed or partially immersed in said body of liquid, has the function of a float. The lever 17 is normally supported in a position to close the valve head 3 by a latch member 22 provided with a lug 23 upon which the extremity of the lever 17 normally engages and which has a beveled under side. The latch member 22 is pivotally supported at its upper end and its lower end projects loosely through an opening in a piston stem 24. The latter works

in a guide lug 25 and carries a head 26 which works in a suitably outlined opening formed beneath the wall 19, the said wall having a lug 27 to arrest the outward movement of the piston head 26. In this construction the reduction of pressure in the distributing pipe results in the unbalancing of the pressure in the casing 1, the pin-hole in the valve 20 being too small to pass any appreciable or substantial degree of pressure from the casing 1 to the distributing pipe. When the pressure in the casing 1 is unbalanced it shifts the body of liquid 9 and in such action produces an outward movement of the piston head 26 as is obvious. Thereupon the member 22 is withdrawn from engagement with the free end of the lever 17 and the latter is permitted to drop, carrying therewith the valve head 3 and uncovering the opening 2. The pressure in the portion C' of the distributing pipe then passes through the pipe 4, lifting the valve 20 and into the casing 1, issuing from the latter at the vent hole 2. The dry pipe valve is then released and as the water passes up the distributing pipe, it backs up into the casing 1, through the connection 4, first causing the closing of the valve 3 by elevating the member 21 to a sufficient extent and ultimately resetting the head 26 and the member 22, the lever 17 being thus again latched in its normal position.

It will be noted, in so far as the embodiment shown is concerned, that the element D is not interposed directly in the distributing pipe but at one side of the same so that the pressure is shunted, so to speak, through said element. For this reason the element D may be readily applied to any existing type of dry pipe water service system which may already have been installed and such application does not involve any modification of or substantial changes in the original installation.

If for any reason whatever, now unforeseen, the element D should fail to work, the operation of the system will proceed in the manner usual with the existing types of construction, since the mediate relation of the element D in so far as the example shown is concerned, is found in its order of operation rather than in its physical structure or assemblage.

The invention is believed to be of considerable novelty within its particular field, for which reason no specific description herein contained is intended to put any limitation upon the scope of the appended claims which does not inhere in the language thereof.

Having fully described my invention, I claim:

1. In a dry pipe water service fire extinguisher system, in combination, a water service pipe, a distributing pipe provided with a valve controlled outlet, a dry pipe valve interposed between the water service

- pipe and the distributing pipe, the distributing pipe containing an elastic fluid under pressure which normally restrains the operation of the dry pipe valve and the operation of the latter being consequent to a reduction of the pressure in the distributing pipe, means operable consequent to the opening of the valve in the distributing pipe for venting pressure from said distributing pipe concurrently with and independently of the venting of pressure at said open distributing pipe valve, the means being connected to the distributing pipe at one side thereof and a check valve located in the distributing pipe in advance of the means. 5
2. In a dry pipe water service fire extinguisher system, in combination, a water service pipe, a distributing pipe provided with a valve controlled outlet, a dry pipe valve interposed between the water service pipe and the distributing pipe, the distributing pipe containing an elastic fluid under pressure which normally restrains the operation of the dry pipe valve and the operation of the latter being consequent to a reduction of the pressure in the distributing pipe, a casing arranged at one side of the distributing pipe, a connection between the casing, a partition defining two communicating liquid chambers within the casing, a body of liquid partially filling the two chambers, the casing receiving pressure from the distributing pipe, means for preventing the pressure in the casing from passing to any appreciable extent into the distributing pipe when the pressure in the latter is reduced consequent to the opening of the valve in the distributing pipe whereby the pressure in the casing at such time shifts the body of liquid, the casing having a vent opening, a valve head normally closing the vent opening, and means operable consequent to the shifting of the body of liquid for causing the valve head to uncover the vent opening, the pressure in the distributing pipe passing through the casing and through the vent opening when the latter is uncovered. 10
3. In a dry pipe water service fire extinguisher system, in combination, a water service pipe, a distributing pipe provided with a valve controlled outlet, a dry pipe valve interposed between the water service pipe and the distributing pipe, the distributing pipe containing an elastic fluid under pressure which normally restrains the operation of the dry pipe valve and the operation of the latter being consequent to a reduction of the pressure in the distributing pipe, a casing at one side of the distributing pipe, the casing having two liquid containing chambers communicating only at their lower ends, a float in one of the chambers, a connection leading from the other chamber to the distributing pipe, the casing having a vent opening, a valve head operatively connected to the float and held to normally close the vent opening and a second connection between the casing and the distributing pipe, the second connection being located in advance of the first connection and containing a fixed diaphragm having a "pin-hole" aperture. 15
4. In a dry pipe water service fire extinguisher system, in combination, a water service pipe, a distributing pipe provided with a valve controlled outlet, a dry pipe valve interposed between the water service pipe and the distributing pipe, the distributing pipe containing an elastic fluid under pressure which normally restrains the operation of the dry pipe valve and the operation of the latter being consequent to a reduction of the pressure in the distributing pipe, a casing located immediately in advance of the dry pipe valve and having a vent opening, an auxiliary valve normally closing the vent opening, means operable consequent to a reduction of pressure in the distributing pipe for causing the auxiliary valve to uncover the vent opening, and a connection through which the pressure in the distributing pipe passes into the casing when the vent opening of the latter is uncovered. 20
5. In a dry pipe water service fire extinguisher system, in combination, a water service pipe, a distributing pipe provided with a valve controlled outlet, a dry pipe valve interposed between the water service pipe and the distributing pipe, the distributing pipe containing an elastic fluid under pressure which normally restrains the operation of the dry pipe valve and the operation of the latter being consequent to a reduction of the pressure in the distributing pipe, a casing located immediately in advance of the dry pipe valve and having a vent opening, an auxiliary valve normally closing the vent opening, means operable consequent to a reduction of pressure in the distributing pipe for causing the auxiliary valve to uncover the vent opening, a connection through which the pressure in the distributing pipe passes into the casing when the vent opening of the latter is uncovered, and a check valve located in the distributing pipe in advance of said connection. 25
6. In a pressure controlled fire extinguisher system, in combination, a source of extinguishing liquid supply, a distributing pipe connected with said source of supply and adapted to contain elastic fluid under pressure, a distributing valve in said pipe, means susceptible to the expansive action of the pressure in the distributing pipe for governing the admission of the extinguishing liquid into said pipe and operable only when the pressure in said pipe falls below a certain value. 30

certain degree, a casing in communication with the distributing pipe and having a vent opening, an auxiliary valve which normally closes the vent opening, a yieldable element operable by a pneumatic impulse and which provides for the operation of the auxiliary valve, the element having air spaces at opposite sides thereof in the distributing pipe and in the casing respec-

tively, and a restricted communication between said respective air spaces.

In testimony whereof I have hereunto set my hand in presence of two subscribing witnesses.
